MILON H. BORZIN AND ARSENIE MITRU, OF CHICAGO, ILLINOIS.

CLOSURE LOCK.

Application filed November 11, 1926. Serial No. 147,830.

This invention relates to closure locks, and especially to an improved combination lock of simple and effective form and including a part of the closure which is movable into and 5 out of the locking position.

One object of the invention is to provide a lock of this character which, while particularly useful in connection with pencil boxes and the like, such as used by school children, 10 is also useful in connection with a closure for boxes and receptacles of other kinds.

Another object is to provide a device of this character which is very simple and comparatively inexpensive while being thoroughly 15 practical and effective.

Another object is to provide a device of this character which can be manufactured with a large number of combinations, so that each box or receptacle of a large number can 20 have a combination differing from the other devices of the said large number.

Other objects and important features are pointed out or implied in the following details of description, in connection with the 25 accompanying drawings in which:

Figure 1 is a top plan view of a box provided with a closure which includes certain essential elements of the combination lock made in accordance with this invention.

30 Fig. 2 is a side elevation of the box shown in Fig. 1.

Fig. 3 is a top plan view of the lid or closure of the box shown in Figures 1 and 2.

Fig. 4 is a top plan view of a metal disk 35 which forms part of the combination lock.

Fig. 5 is a bottom plan view of the upper lock member having a coiled spring fitted around its central opening.

Fig. 6 is a longitudinal central sectional 40 view through the combination lock including the closure shown in Figs. 3 and 7.

Fig. 7 is an end view of the cover or closure.

Fig. 8 is a detail view showing a modified 45 form of the interlocking end wall and closure.

Referring to these drawings in detail, in 50 which similar characters correspond with similar parts throughout the several views, and in which the elongated structure here shown is illustrative of one of the many forms to which this invention is applicable: The main body 10 of the box consists of a bottom, side walls, and end walls, the latter being indicated at 11 and 12 respectively. The end wall 11 is preferably the same height as the side walls, and is relatively thick to provide 55 a secure anchorage for a pivotal member 13

which may be either a screw or other form of headed fastener. However, this member 13 is preferably immovably secured in the end 11, so the lock can not be taken apart or 60 disassembled, and therefore, the box can not

be opened without breaking it or operating the lock according to its particular combination. In securing the fastening member 13 in place, its shank may be driven into an 65 aperture of the end member 11, which aperture is sufficiently small to insure a tight fit of this anchoring member or pivot of the rotary lock member which is indicated at 14, this lock member being centrally or axi-

ally bored to snugly fit around the upper or headed part of the pivotal member 13. This member 14 is provided with an annular series 70 of pointers or index elements 15 each provided with an adjacent index numeral which

refers thereto. These index elements range from 1 to 12, inclusive, in the device here 75 illustrated, although there may be a greater or less number of such index elements in other forms of the invention. The lid or

closure 16 is provided with an arrow or other form of index element 17, preferably in the longitudinal center of the closure 16, and this closure is adapted to be slid longitudinally and swung horizontally about the pivot 13 80

when the combination knob or rotary element 14 has been properly manipulated, according to the combination of the lock, and stopped with the proper index elements 15 in registration with the index elements 17, 90 as will presently appear.

Referring now to Figs. 3 and 6, it will be seen that the closure 16 has a slot 18 therethrough, and between this slot and the index element 17 is secured a stud 20. This stud 95 extends into an annular recess 21 of the member 14. A radially disposed recess 22 is in open communication with the recess 21 and is adapted to receive the stud 20 when the closure 16 is slid longitudinally toward its 100 pivotal member 13. The member 14 is also formed with an annular recess 23 around the central bearing opening which receives the pivot 13, and within this latter recess is fitted a compression spring 24 which is of 105 helical formation and surrounds the pivot member 13. This spring 24 bears upon a disk or lock member 25 such as shown separately in Figure 4, and this member is preferably of sheet metal, has a central bearing opening 26 which fits around the pivot 13, has a 110 radially disposed slot or notch 27 which is

adapted to receive the stud 20, and has an upright stud or lug 28 which is preferably struck up from an aperture in the body of this disk. This stud 28 cooperates with a depending 5 stud or lug 29 of the rotary lock member 14, and in this connection, it is pointed out that either of these studs 28 or 29, or both of them, may be in any one of an infinite number of positions, respectively, but essentially in 10 position to cooperate with one another, that is, the stud 28 must be in the path of the stud 29 during rotation of the latter, and the cooperation of these studs effects rotation of the lock member 25 by the lock member 14. 15 It will be seen that the member 25 lies flat against the upper surface of the member 16, so all parts of this lower surface frictionally engage with the upper surface of the member 16. There is no frictional engagement of the 20 member 14 against the upper surface of the member 25, and the frictional engagement of the spring 24 is confined to the central part of the disk 25, and therefore, the pressure of the spring 24 against the member 16 causes this 25 disk 25 to remain stationary while the member 14 is being rotated and while the studs 28 and 29 are not in engagement with one another. However, when the member 29 comes into contact with the member 28 and 30 continues its rotation, it carries the disk 25 therewith, and if its rotation is discontinued when the notch 27 is between the stud 20 and the pivot 13, the lid 16 could be slid toward the pivot 13 if the notch 22 was also in registration with the stud 20. However, the relative 35 positions of the studs 28 and 29 to the notches 22 and 27 should be such that these notches 22 and 27 are out of registration with one another when the studs 28 and 29 are co- 40 operating with one another, so it is necessary to turn the recess 22 into registration with the recess 27 after the latter has been placed into registration with the stud 20; so now, the closure 16 can be slid toward the pivot 13, carrying its stud 20 into the registering recesses 22 and 27, and now, the closure 16 can be 45 swung around the pivot 13 for opening the box.

The box-end 12 has an upward extension 50 12^a against which the opposite end of the closure 16 abuts, and this part 12^a may be provided with a dove-tail notch such as indicated at 12^b of Figure 1, to receive a dove-tail projection 16^a of the closure 16, or the 55 closure may be such as shown in Fig. 8 in which it is indicated by the reference character 160, having a beveled end 160^a, and the end 120 having an undercut element 120^a, so this end of the closure cannot be lifted because 60 it is locked down by the undercut surface 12^b (Fig. 1) or 120^a of Fig. 8. These two forms of interlocking elements at the left ends of Figures 1 and 8 serve to show that this interlocking arrangement is not confined to any specific form, and obviously, one or more 65

dowels (not shown) might be employed for connecting the closure in interlocking engagement with the upper end of the end wall member opposite to that which contains the pivot 13 and its adjuncts. 70

For opening the box, the rotary member or knob 14 is first turned in one direction, for instance, counter-clockwise until the proper index member 15 registers with the index member 17, thereby indicating that the notch 75 27 is registering with the stud 20, and then the rotary member 14 is turned in the opposite or clockwise direction, so its stud 29 leaves the stud 28, and so the notch or recess 22 remains in registration with the stud 20 while the knob or rotary member 14 is continued in its movement until the proper index member 15 registers with the index member 17 for indicating that the recess 22 is registering with the stud 20; and now, both 80 recess 22 and 27 being in registration with the stud 20, the user grasps the closure 16 and slides it toward the stud 13 until the dovetail part 16^a is out of the notch 12^b, or until the beveled end 160^a is removed a sufficient 85 distance from the undercut part 120^a to permit the closure to be turned about the pivot 13. 90

From the foregoing, it is seen that we have 95 provided a very effective and comparatively inexpensive device which is capable of many uses, and which is susceptible of various changes of construction and arrangement within the scope of the inventive ideas as implied, and claimed hereinafter. 100

In manufacturing these devices, the disks such as shown in Figure 4 may have their studs 28 placed in various positions, and this may be effected by any appropriate means. 105 Instead of these lugs 28 being struck up, the disks 25 may be formed with an annular series of apertures, and the lugs may be separately formed and each forced into any one of such apertures, thereby varying the positions of the lugs 28 in accordance with the respective combinations of the devices. 110

What we claim as our invention is:

1. The combination in a box or the like having side walls and end walls, a closure thereon and having substantially interlocked engagement with one of said end walls, a pivot extending from the other one of said end walls; said closure having a slot through which said pivot extends, a stud extending up from said closure, and a rotary member 115 on said pivot and having an annular recess and a radially disposed recess communicating with one another and adapted to receive said stud alternately, for the purpose specified. 120

2. The combination in a box or the like having side walls and end walls, a closure thereon and having substantially interlocked engagement with one of said end walls, a pivot extending from the other one of said end walls, said closure having a slot through 130

which said pivot extends, a stud extending up from said closure, a rotary member on said pivot and having an annular recess and a radially disposed recess communicating 5 with one another and adapted to receive said stud alternately, a disk seated on said closure and journaled on said pivot and having a radially disposed recess adapted to register with the recess of said rotary member, 10 means on said rotary member for rotating said disk so as to bring its recess into and out of registration with said stud, and a spring between said rotary member and said disk for holding the latter in frictional en-

gagement with said closure and thereby preventing untimely rotation of the disk during partial rotation of said rotary member, for the purpose specified. 15

3. The structure defined by claim 1, and index members carried by said closure and rotary member and adapted to register with one another for indicating when said stud is in registration with said radially disposed recess. 20

In testimony whereof we affix our signatures. 25
